UNITED STATES PATENT OFFICE

2,245,472

PRESSER PLATE FOR DISPENSING
MACHINE FEED TABLES

Lewis Walter Goldstein, New York, N. Y., assignor to Lipton Manufacturing Co., Inc., New York, N. Y.

Original applications July 18, 1939, Serial No. 285,153, and September 18, 1939, Serial No. 295,536. Divided and this application March 30, 1940, Serial No. 326,998

10 Claims. (Cl. 271—2.1)

This invention relates to tape dispensing machines and is a division of my copending application, Serial No. 295,536, filed September 18, 1939, for Presser plate for tape dispensing machines, now Patent No. 2,209,266, July 23, 1940, and also of my Patent No. 2,175,959 which issued October 10, 1939.

An object of this invention is to provide an improved presser plate in association with a tape guiding and feeding table which is interposed between a tape severing means and a tape feeding wheel, the presser plate being so constructed that it will not obstruct the movement of the tape over the table, the said tape guiding and feeding table, tape severing means and feeding wheel being in the form disclosed in the application and patent aforesaid.

Another object of this invention is to provide a presser plate of this kind which is adapted to be fixed in its adjusted position relative to the table, the plate including an improved clamping means for holding the plate in adjusted position.

A further object of this invention is to provide a presser plate of this kind in combination with a tape feeding table having a tape guiding channel, the presser plate being formed in such a manner that in its lowermost position relative to the table the plate will not bind against the tape.

A still further object of this invention is to provide a presser plate of this kind which may easily be replaced or removed for cleaning or repairing the machine.

To the foregoing objects and to others which may hereinafter appear, the invention consists of the novel construction, combination and arrangement of parts as will be more specifically referred to and illustrated in the accompanying drawing wherein are shown embodiments of the invention, but it is to be understood that changes, variations and modifications may be resorted to which fall within the scope of the invention as claimed.

In the drawing:

Figure 1 is fragmentary vertical section of a tape dispensing machine embodying my invention;

Figure 2 is a sectional view taken on the line 2—2 of Figure 1; and

Figure 3 is a sectional view taken on the line 3—3 of Figure 1.

Referring to the drawing, the numeral 10 designates generally a housing provided with parallel side walls 11 and a cover 12 which is formed on the opposite longitudinal edges thereof with

depending flanges 13 snugly engageable with the upper edges of the side walls 11 so as to removably secure the cover 12 on the housing 10.

The form of tape dispensing machine shown in Figure 1 is more specifically described in my copending application, Serial No. 295,536 and my Patent No. 2,175,959. Briefly, the tape dispensing machine shown in Figure 1 includes a feeding device in the form of a relatively large feeding wheel 14 which is fixed to a drive shaft 15 and an idler feeding wheel 16 is rotatably carried by an idler shaft 17. The shaft 17 is removably mounted in vertically disposed guide members 18 which are carried by the inner surfaces of the side walls 11 and a spring 19 engages the shaft 17 and constantly urges the idler wheel 16 into engagement with a strip of tape T which is moved forwardly over a tape feeding table generally designated as 20 and which is secured between the two side walls 11.

A tape severing mechanism generally designated as 21 is disposed at the forward end of the table 20 and is operated by means of a rock lever 22. The rock lever 22 is operated from a lever tripping member 23 which is carried by the drive shaft 15. A tape moistening device generally designated as 24 is disposed forwardly of the tape severing mechanism 21 and includes a moistening brush 25 disposed in a reservoir 26. A presser plate structure generally designated as 27 is adjustably mounted between the two side walls 11 forwardly of the severing mechanism 21 and is adapted to maintain the tape T in contact with the bristles of the moistening brush 25. The specific details of the moistening structure 24 including the presser plate 27, is embodied in my copending application, supra.

The feeding table 20 includes a table member 28 which has disposed along the opposite longitudinal edges, a pair of upstanding ribs 29. The ribs 29 with the table member 28 form a tape guiding channel 30 within which the tape T is adapted to be moved by the feeding wheel 14.

A presser plate generally designated as 31 is interposed between the idler feed wheel 16 and the severing mechanism 21 and comprises a plate-like body 32 which is tapered or bevelled at its forward end as at 33. The body 32 is provided along the opposite longitudinal edges thereof with a rabbeted portion 34 within which the ribs 29 engage so that the downwardly offset intermediate portion 35 of the body 31 will extend downwardly into the tape feeding channel 30. The two side walls 11 on the inner faces

thereof are each provided with a pair of parallel guide members 36 and the body 32 is provided with a pin or trunnion 37 on each side thereof which is adapted to slidably engage between the pair of guide members 36. The guide members 36 and the pin or trunnions 37 serve as positioning means for positioning the presser plate 31 in the desired position between the idler feed wheel 16 and the severing mechanism 21. The body 32 at the rear thereof is provided with a concave recess 38 within which the idler wheel 16 and a portion of the spring 19 are adapted to loosely engage. By providing the recess 38 at the rear of the body 32, the body 32 is formed with a pair of rearwardly directed wings 39 which are disposed on opposite sides of the idler feed wheel 16 and also on opposite sides of the feeding wheel 14.

The body 32 on its upper side is provided with a pair of upstanding spaced apart parallel ribs or guide members 40 which extend transversely across the body 32. A longitudinally bowed presser plate clamping member 41 extends transversely across the body 32 and is of such a width that the clamping member 41 may loosely engage between the ribs 40. The clamping member 41 is normally of a length when in bowed form and when relieved of tension, that the ends thereof will loosely engage the guide members 36 so that the presser plate 31 may be vertically adjusted relative to the table 20. A threaded tensioning member including a bolt 42 provided with a knurled head 43 engages through an opening 44 formed in the center of the clamping member 41 and the bolt 42 is threaded into a threaded opening 45 formed in the body 32 substantially centrally of the channel formed by the two parallel ribs 41.

In the use and operation of this presser plate in association with the tape dispensing machine embodied in my copending application hereinbefore mentioned and in my Patent No. 2,175,959, the plate 31 is removably mounted between the side walls 11 with the slide members or pins 37 loosely engaging between the vertical guide members 36 carried by the side walls 11. The presser plate 31 may be initially lowered until the rabbed portions 34 thereof engage the channel forming ribs 29 of the table 20. In the event the tape T is of such a thickness that the underside of the offset portion 35 of the plate 31 will frictionally engage the tape T, the plate 31 may be raised slightly by loosening the tensioning bolt 42 and then tightening this bolt so as to cause the opposite ends of the clamping member 41 to tightly engage the inner faces of the guide members 36.

If desired, the presser plate 31 may be disposed with the undersurface thereof, substantially parallel with the confronting face of the table 20, or the presser plate 31 may be tilted downwardly at its forward end so that the forward or bevelled end 33 of the presser plate 31 will be closer to the surface of the tape T than the opposite or intake end of the presser plate 31. In this manner the presser plate 31 will form a forwardly reducing guide channel which tapers in the direction of the severing mechanism 21. In actual practice the presser plate 31 is preferably so positioned relative to the table 20, that the tape T may freely move within the tape guiding channel 30.

It has been found from past experience that contact of the presser plate 31 with the tape mov-

ing over the feeding table will frequently cause the tape to buckle under the action of the feeding mechanism whereas with a presser plate as constructed according to this invention, the presser plate will not at any time cause any friction between the tape T and the table 20. The purpose of the presser plate 31 is to guide the tape T toward the severing and moistening mechanism and to guide the tape in such a manner that the tape will not buckle as it is pushed forwardly by the feeding mechanism.

The provision of a vertically adjustable presser plate permits the use of different thicknesses of tape, it being understood that certain tapes are provided with a relatively thick coating of adhesive, whereas other types of tapes are formed of thin paper and a fairly thin coating of adhesive. By providing a presser plate as hereinbefore described, the tape dispensing machine can be readily and quickly adjusted to accommodate different types or thicknesses of tape which it may be desired to use in the tape dispensing machine. It is well known that certain tape dispensing machines are available which use a spring pressed presser plate for maintaining the presser plate in contact with the tape moving over the feeding table and certain other types of machines embody the use of a relatively heavy presser plate which is pivotally mounted between the side walls of the housing and gravitantly engages the surface of the tape. However, these types of presser plates have caused considerable difficulty in the operation of the dispensing machine in that the dispensing machine cannot be used for different thicknesses of adhesive tape, and it is necessary for the proper operation of such dispensing machine that the tape be relatively stiff so that it can be pushed forwardly by the tape feeding mechanism.

However, with a presser plate as hereinbefore described, the thickness of the adhesive tape will not have any effect on the successful operation of the tape dispensing machine as the presser plate 31 can be easily and quickly adjusted to accommodate different thicknesses of adhesive tape and the presser plate associated with the moistening device may also be finely adjusted as described in my copending application to accommodate different kinds of adhesive tape.

What I claim is:

1. In a tape dispensing machine, a tape guiding table, longitudinal ribs extending upwardly of the opposite edges of the table, a presser plate above said table, opposed vertical guides extending upwardly of opposite edges of said table, means carried by said plate slidably engaging said guides, and means carried by said plate engageable with said guides for holding said plate in adjusted position relative to said table.
2. In a tape dispensing machine, a housing, a tape guiding table carried by said housing, a pair of spaced apart parallel longitudinal ribs extending upwardly of said table and forming a guide-way therebetween, a presser plate above said table, vertical guide members carried by said housing extending upwardly of opposite edges of said table, means carried by said plate engaging said guide members, a plate clamping member having its ends engaging said guide members, and means engaging said plate and said clamping member for holding said plate in adjusted position relative to said table.
3. In a tape dispensing member including a housing, a tape guiding table in said housing, a

pair of longitudinal ribs carried by said table and forming a guideway therebetween, a presser plate above said table and adapted in one position thereof to engage on said ribs, coacting guide means carried by said housing and said plate, an upwardly projecting part carried by said plate, a longitudinally bowed clamping member having its ends engaging said coacting guide means, and means engaging said part and said clamping member for holding said plate in adjusted position relative to said table.

4. In a tape dispensing member including a housing, a tape guiding table in said housing, a pair of longitudinal ribs carried by said table and forming a guideway therebetween, a presser plate above said table and adapted in one position thereof to engage on said ribs, coacting guide means carried by said housing and said plate, an upwardly projecting part carried by said plate, said part having a channel therein extending transversely of said plate, a longitudinally bowed resilient clamping member disposed with the opposite ends thereof in said channel and engaging said coacting guide means, and a tensioning member engaging through said member and threaded into said part for adjustably securing said plate relative to said table.

5. A presser plate for a tape guiding and feeding table comprising a plate-like body, a pair of upstanding spaced apart parallel ribs carried by said body and extending transversely thereof, a longitudinally bowed resilient clamping member disposed with the concave side thereof lowermost and the opposite ends slidably engaging between said ribs, and a threaded tensioning member engaging through said clamping member and threaded into said body.

6. In a tape dispensing device including a housing provided with side walls, a tape guiding table between said side walls, longitudinal ribs at the opposite edges of said table forming a tape guiding channel therebetween, a presser plate engaging over said table, said plate having rabbeted opposite edge portions engaging said ribs to thereby offset downwardly a portion of said plate between said ribs, means carried by said plate and engageable with said side walls for releasably clamping said plate in adjusted posi-

tion relative to said table, and means providing for the said other means to releasably engage said side walls.

7. The combination with a tape dispensing machine comprising a housing having side walls, a tape guiding table between said walls, guide means carried by said walls on the inner sides thereof and extending upwardly of said table, a presser plate between said walls and above said table, said plate comprising a body member, a pair of parallel spaced apart ribs carried by said member and extending transversely thereof, laterally extending guide engaging members carried by said body member, a longitudinally bowed clamping member engaging between said ribs, and a threaded tensioning member engaging through said clamping member for tensioning the opposite ends of said clamping member against said guide means to thereby fixedly hold said body in adjusted position relative to said table.

8. In a tape dispensing machine including a housing having side walls, and a tape guiding table between said walls; a presser plate above said table, and tensionable means carried by said plate engageable with said walls for fixedly holding said plate relative to said table.

9. A presser plate for a tape guiding and feeding table comprising a plate-like body, a clamping member disposed transversely of said body and having the opposite ends thereof shiftable relative to the opposite edges of the body, and means engaging said member and said body for shifting the ends of said member relative to the opposite edges of the body to an extent to thereby fixedly hold said plate-like body in adjusted position relative to the table.

10. In a tape dispensing machine including a housing having side walls and a tape guiding table between said walls; a presser plate adjustably supported above said table, and adjustment means for and carried by said plate engageable with the inner faces of the said side walls in the adjusted position of said plate for holding said plate in a fixed position of adjustment relative to said table.

LEWIS WALTER GOLDSTEIN,
